UNITED STATES PATENT OFFICE.

GABRIEL HENRY, OF QUEBEC, QUEBEC, CANADA.

TRAFFIC-REGISTER.

1,368,798.

Specification of Letters Patent. Patented Feb. 15, 1921.

Application filed March 9, 1920. Serial No. 364,433.

To all whom it may concern:

Be it known that I, GABRIEL HENRY, a citizen of Canada, and a resident of Quebec, in the Province of Quebec and Dominion of Canada, have invented a new and Improved Traffic-Register, of which the following is a full, clear, and exact description.

This invention relates to improvements in traffic registers, an object of the invention being to provide improved means for photographing the traffic on a street or road and provide improved means for operating a picture film and improved means for automatically taking pictures of the vehicles as they pass a given point on the road so that the film, when developed, can be utilized in connection with a projecting device to illustrate the traffic of the road and can be maintained as a permanent record.

The registering of traffic on the highways is very important and is becoming more and more urgent because of the fact that before deciding the amount of money to be invested in a certain road and the kind of pavement to be adopted for it, it is necessary to obtain full information concerning the amount and the nature of the traffic on this road.

Highway engineers are much handicapped by lack of proper information on the subject and the means usually employed heretofore is to appoint special officers who take a position at a certain point on the road and make a report of the traffic. The highway engineers must depend upon the word of the officer and obtain such detailed information as he can gather and this is more or less unsatisfactory.

It is the purpose of my invention to provide a systematic, automatic and continuous registration of the actual traffic at any point on the highway and this problem I believe my invention to thoroughly and efficiently solve.

It is the object of my invention to provide an apparatus which will take a quick snapshot so that vehicles of all speeds can be photographed and also provide an apparatus which will visualize the kind of vehicles passing and which will prevent more than a single picture being taken of a single vehicle.

It is also the object of my invention to provide an apparatus which will take pic-

tures of all vehicles passing on any part of the width of the road and which will not interfere with the traffic.

A further object is to provide an apparatus which will be automatic so as not to require the continuous attendance of an operator, but only occasional inspection and from time to time to remove and replace films.

A further object is to provide an apparatus which will be strong and durable and which will not be injured by the elements.

It is, of course, obvious that my invention might be used at night as well as in the daytime by provision of suitable lights to illuminate the highway.

With these and other objects in view the invention consists in certain novel features of construction, and combinations and arrangements of parts as will be more fully hereinafter described and pointed out in the claims.

In the accompanying drawings—

Figure 1 is a diagrammatic plan view partly in section illustrating my invention; 80

Fig. 2 is a view in section on the line 2—2 of Fig. 1;

Fig. 3 is an enlarged view in section on the line 3—3 of Fig. 2;

Fig. 4 is a perspective view of one of the 85 grates 10;

Fig. 5 is a view in section on the line 5—5 of Fig. 6;

Fig. 6 is an enlarged view in vertical transverse section through one of the contact boxes 12; 90

Fig. 7 is a diagrammatic elevation illustrating an improved arrangement of electric circuits;

Fig. 8 is a view in vertical section through 95 the camera box taken on the line 8—8 of Fig. 11, showing the parts in one position;

Fig. 9 is a view similar to Fig. 8 showing the parts in another position;

Fig. 10 is a view in vertical section 100 through the camera box taken on the line 10—10 of Fig. 11;

Fig. 11 is a view in transverse section of the camera box, taken on the line 11—11 of Fig. 8; 105

Fig. 12 is a fragmentary view in vertical transverse section on the line 12—12 of Fig. 8; and

Fig. 13 is a fragmentary view in section on the line 13—13 of Fig. 10. 110

Referring particularly to Figs. 1, 2, 3, 4, 5 and 6, 1 represents a road or highway having a house or building 2 located opposite the same. A concrete lined trench 3 is provided 5 across the road or highway and is preferably of a size sufficient to permit the entrance of a man to inspect and clean the same. This trench 3 preferably inclines or slopes from one end to the other so as to deposit into a basin 4 having a clean-out or manhole cover 5 above the same.

10 Across the top of the trench and flush with the roadway I provide a series of grates 10, one of which is shown in perspective in Fig. 15 4. Each grate 10 is covered by an elastic steel plate 6 bolted at its ends to the grate as shown at 7, and the upper surfaces of the grates are depressed at their centers, as shown at 8, to allow a predetermined amount 20 of vertical movement of the intermediate portions of the steel plates 6 for a purpose which will hereinafter appear.

25 Each grate 10 is made with a central opening 9 in which a vertically movable pin 11 is mounted and this pin 11 may be of insulation or other non-conducting material. To the bottom of all the grates metal contact boxes 12 are secured and these contact boxes contain elastic contacts 13 and 14 normally 30 apart and positioned under the flexible elastic covers 15 of the contact boxes. Each contact box has secured to the under face of its cover a block 16 preferably of insulation so that when the cover 15 is depressed, 35 the block 16 will act to force the contacts 13 and 14 together.

40 I have illustrated the contacts 13 and 14 as metal bails crossing each other and spaced apart with each bail provided with a binding post 16" which is electrically connected with my improved mechanism as will be explained.

45 To further insure the closing of the circuits, a strip 17 which may be in sections is located on top of the plate 6 so that the engagement of a vehicle wheel with this strip 17 insures a depression of at least one of the pins 11 to close the electric circuit.

50 In the house or building 2, I locate a camera box 18 which is so positioned that the mechanism therein contained will operate to take pictures of the vehicles moving along the highway. The box 18 is divided by a partition 19 into two compartments 20 and 21 respectively. In the compartment 20 I provide a pair of operating rolls 22 and 23 having teeth 24 thereon to engage the perforations of a film 25 to cause the film to move past an opening 26 to expose the same 55 when a shutter 27 is operated. I have not illustrated any particular form of shutter, but it is, of course, to be understood that at each operation the shutter opens and then closes as is true with the ordinary snapshot 60 shutter in general use.

A plate 28 is provided to hold the film straight and flat against a perforated metal plate 29 and a block of glass 30 having spring held arms 31 is located against the film in line with the opening 26 to maintain 70 the film perfectly flat and smooth at its point of exposure. The plate 28, above referred to, has a central guiding sleeve 32 for the plate of glass 30.

75 Removable reel boxes 33 and 34 are provided in the upper and lower portions of the compartment 20 and these boxes support shafts 35 on which the reels 36 carrying the film 25 is mounted. It is obvious that the film from one reel passes onto the other and 80 openings 37 are provided in the boxes for the passage of the film, and guide rollers 38 are also provided to properly direct the film through the openings 37.

85 I preferably employ reels 36 as shown in section in Fig. 11, these reels being provided with metal sleeves or bushings 39 to receive the shafts 35 and provide for pins 40 carried by the reels which project into longitudinal grooves 41 in the shafts to compel 90 the shafts and reels to turn together, but permit removal of the reels as occasion may require. I also preferably provide spring plates 42 on the reels to clamp the ends of the film and insure a locking engagement 95 therewith.

100 The upper reel 36 is provided outside of the box with a friction pulley 43 engaged by an elastic belt 44 secured to the box 33 so that the necessary frictional resistance is offered to the turning of the reel to prevent any slack of film in the box.

105 To insure the proper engagement of the film with the rolls 22 and 23, I provide two pairs of pivoted arms 45 and 46 and locate hubs 47 on the pivotal axes of the said arms 45 and 46. The hubs of the pairs of arms are connected by coiled springs 48 secured at their ends to the respective hubs so that 110 these springs exert a tension to pivot the arms and press rollers 49 at the free ends of the arms against the film to hold the same against the rolls. These rollers 49 are preferably grooved to allow for the projecting teeth 24 of the rolls.

115 The rolls 22 and 23 are fixed to shafts 50 and 51 respectively, the lower shaft 51 supporting within the compartment 21 a ratchet toothed wheel 52 and a friction pulley 53. The lower shaft 51 also projects into the 120 compartment 21 and is provided with a friction pulley 55 and a friction belt 56 is positioned around the pulleys 53 and 55 compelling them to turn together.

125 It will be noted that the pulley 55 is appreciably smaller than the pulley 53 so as to give the necessary movement to the film at each operation of the ratchet toothed wheel 52, as will now be described.

130 A bracket 57 in the compartment 21 sup-

ports a rocker shaft 58 and also an electric magnet 59 below the same. A crank arm 60 is secured to the rocker shaft 58 and an armature 61 is also secured to the rocker shaft 58 and is adapted to be attracted by the magnet 59 to return the crank arm 60 to normal position, which is shown in Fig. 8. This crank arm 60 carries a pawl 62 which engages the toothed wheel 52 and is also connected by a link 63 with a bell crank lever 64 operating the shutter 27. A pawl 62' holds the wheel 52 from revolving reversely.

A crank arm 65 is fixed to the shaft 58 and is held in normal horizontal position, as shown in Fig. 8, by means of an armature 66 which has a notch 67 in its face receiving the end of the arm 65. The armature 66 is supported by a spring 68 and is controlled by a relay magnet 69.

20 A pulley 70 is secured on the rocker shaft 58 and a coiled spring 71 is extended around this pulley and fixed thereto at one end and at its other end is fixed to the lower portion of the bracket 57. This spring 71 exerts a pull on the pulley 70 so that when the armature 66 is attracted by the magnet 69 and moved away from the end of the arm 65, the spring 71 will turn the rocker shaft 58 moving the parts to the position shown in Fig. 9.

30 The magnet 69 is included in an electric circuit with a battery or source of electricity 72 and with all of the contact boxes 12, the latter being electrically connected in series with wires 73 and 74 and these wires connected to the magnet 69 and including in their circuit the source of electricity 72.

Above the arm 65 a bell crank lever 75 is pivotally mounted as shown at 76, and at one end engages the plunger 77 of a dashpot 78, while a coiled spring 79 connects the plunger 77 with a fixed part of the box and exerts a continuous pull thereon holding the lever 75 in the normal position shown in Fig. 8. A coiled spring 80 connects the lever 75 with the arm 65 so that the arm and the lever are compelled to move together when the arm 65 is moved downwardly.

40 A contact carrying arm 81 is supported on and movable with the lever 75. This arm 81 at its free end carries a pair of spring contacts 82 normally apart and these contacts are forced together by the lever 75 which at its free end has a block of insulation 83 and which engages the contacts and compresses them between the said block 83 and a roller or other insulated member 84 on the arm 65. The contacts 82 are connected by wires 85 and 86 with the magnet 59 and include in their circuit a battery or other source of 50 electricity 87.

60 The operation of my improved apparatus is as follows: When a vehicle passes over the strip 17, the weight of the vehicle causes the closing of the circuit through the medium of the contacts in one of the contact

boxes 12 to energize the relay magnets 69. When this magnet 69 is energized, it will attract the armature 66 releasing the arm 65 to allow the spring 71 to partially turn the rocker shaft 58 and move the arm 60 and 70 the other parts to the position shown in Fig. 9. This movement of the arm 60, through the medium of the link 63 and bell crank lever 64, causes the operation of the shutter 27 to take a picture of the passing vehicle on 75 the film 25.

When the arm 65 is turned down, the roller 84 withdraws from the pair of spring contacts 82 by the fact that the movement of the lever 75 and of the arm 81 attached to it is made slower by the dashpot 78. It is only a few seconds later that the springs 82 come in contact with the roller 84, are pressed by it against each other and against the block of insulation 83 and that the circuit is closed, thus allowing the lever 65 the time necessary for coming to the position of Fig. 9 and to operate the shutter 27 before being turned up by the armature 61. As soon as the contact in 82 is made the armature 61 is attracted and the lever 65 is returned to the position shown in Fig. 8, but it is only a few seconds later that the dashpot allows the lever 75 to come back completely to its former position and to open 90 the contact 82, the arm 65 at that time being held in position by the notch in the armature 66.

In short, by the disposition adopted the following results are obtained. 100

1st.—The shutter is operated quickly, the arm 65 being turned down without its movement being hindered by any current in the circuit.

2nd.—Between the time of the closing of 105 the road's circuit and the time when the arm 65 is restored to its former position no picture of the rear wheels of the vehicle can be taken.

3rd.—The contact 82 is opened only when 110 the arm 65 is held in position by the notch in the armature 66, so avoiding undue oscillation or vibration of this arm 65.

It will thus be noted that my improved apparatus is entirely automatic in its operation and that the passage of a vehicle over the strip 17 causes the taking of the picture of such vehicle and hence, every vehicle that passes over the strip is photographed and as the pictures are taken upon a moving film, 115 120 they are maintained in their regular order and the film will give a permanent record of the traffic on the road for any given period of time.

Various slight changes may be made in 125 the general form and arrangement of parts described without departing from the invention, and hence I do not limit myself to the precise details set forth but consider myself at liberty to make such changes and altera- 130

tions as fairly fall within the spirit and scope of the appended claims.

I claim:

1. The combination with a highway having a trench across the same, of grates at the upper portion of the trench, elastic plates above the grates, contact boxes below the grates, means connecting the plates and the contacts in the boxes, whereby the passage of a vehicle over a plate causes the closing of the contacts in the box connected therewith, a camera, and electrically operated means for the camera electrically connected with said contacts.
- 15 2. The combination with a highway having a trench across the same, of grates at the upper portion of the trench, elastic plates above the grates, contact boxes below the grates, means connecting the plates and the contacts in the boxes, whereby the passage of a vehicle over a plate causes the closing of the contacts in the box connected therewith, a motion picture camera located adjacent the highway, electrically operated means for the camera, and a relay controlling said last-mentioned means and electrically connected with said contacts.
- 30 3. The combination with a highway having a trench across the same, of a series of grates at the top of the trench flush with the highway, elastic plates on the grates, contact boxes below the grates having contacts therein normally apart, vertically movable pins supported by the grates and adapted to be moved by the plates to close the contacts in the boxes, an electrically operated camera near the highway, and a relay controlling the operation of the camera operating means and electrically connected with said contacts.
- 35 4. The combination with a highway having a trench across the same, of a series of grates at the top of the trench flush with the highway, elastic plates on the grates, contact boxes below the grates having contacts therein normally apart, vertically movable pins supported by the grates and adapted to be moved by the plates to close the contacts in the boxes, an electrically operated camera near the highway, a relay controlling the operation of the camera operating means and electrically connected with said contacts, and a strip extending across the highway above all of said elastic plates.
- 50 5. In an apparatus of the character described, the combination with a camera box and means therein for supporting a movable film, of a ratchet wheel adapted to move the film, a rocker shaft, an arm on the rocker shaft, a pawl on the arm engaging the ratchet wheel, a spring for moving said arm in one direction, and a magnet for moving the arm in the other direction.
- 55 6. In an apparatus of the character de-

scribed, the combination with a camera box 65 and means therein for supporting a movable film, of a ratchet wheel adapted to move the film, a rocker shaft, an arm on the rocker shaft, a pawl on the arm engaging the ratchet wheel, an armature on said rocker shaft, a magnet controlling the position of the armature, a spring adapted to move the shaft in a direction opposite to the movement imparted by the magnet, and an electric relay controlling the operation of the 75 rocker shaft.

7. In an apparatus of the character described, the combination with a camera, of a motion picture film in the camera, a rocker shaft, a spring tending to turn the rocker 80 shaft in one direction, and an electro-magnet tending to turn the rocker shaft in the other direction, means on the rocker shaft for imparting a step-by-step feed to the film, and a relay magnet controlling the operation of the rocker shaft.

8. The combination with a motion picture camera, of a rocker shaft controlling the operation of the camera, a spring tending to turn the rocker shaft in one direction, an 90 armature on the rocker shaft, a magnet adapted to attract the armature and turn the rocker shaft in a direction opposite to the motion imparted by the spring, an arm on the rocker shaft, an armature engaging said 95 arm and holding it against movement, a relay magnet controlling the last-mentioned armature, a pivoted lever, a spring connecting the pivoted lever and the arm, and a pair of electric contacts included in circuit 100 with the first-mentioned magnet and moved together by the said lever when the said arm is released from its engagement with the armature.

9. The combination with a motion picture 105 camera, of a rocker shaft controlling the operation of the camera, a spring tending to turn the rocker shaft in one direction, an armature on the rocker shaft, a magnet adapted to attract the armature and turn 110 the rocker shaft in a direction opposite to the motion imparted by the spring, an arm on the rocker shaft, an armature engaging said arms and holding it against movement, a relay magnet controlling the last-mentioned 115 armature, a pivoted lever, a spring connecting the pivoted lever and the arm, a spring connecting the arm and the lever compelling them to move together, said contacts located between the free end of the lever and the 120 arm and moved together by the pressure of the free end of the lever when the arm is released from its engagement with the armature, a dashpot controlling the operation of the lever, and said contacts included in electric 125 circuit with said first-mentioned magnet.

GABRIEL HENRY,
